UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

UPPER-PULLING MACHINE

Application filed March 19, 1923, Serial No. 626,083. Renewed April 24, 1929.

This invention relates to machines for use in the manufacture of boots and shoes for working uppers over lasts. The invention is herein set forth as embodied in a pulling-over machine, and has for one of its principal objects to provide means for operating on the upper farther rearwardly than has been the practice heretofore in the use of pulling-over machines, for example at the rear of the ball line where the sides of the last curve inwardly from the ball toward the shank.

Machines that are used for pulling over uppers, with or without toe lasting means, are commonly provided with means for pulling the upper at the end of the toe and at the opposite sides of the forepart at or near the location of the tip seam. After the pulling-over operation the sides of the shoe are lasted by the use of a machine of the "hand method" type. It is the common practice for the operator of the side-lasting machine first to mount the shoe on a spindle and by the use of hand pincers to pull the upper inwardly and usually somewhat forwardly over the bottom of the last at the rear of the ball line, where the sides of the last and the edge of the sole or insole (herein frequently referred to generically as the "sole") curve inwardly toward the shank portion of the shoe, and by driving tacks to fasten the upper in those locations, these operations being performed first at one side of the shoe and then at the other side. This procedure is usually regarded as necessary for satisfactory results in side lasting, principally for the reason that the side-lasting machine, which operates on a shoe supported and controlled by the operator, is not well adapted to apply to the upper as hard a pull as is needed in the locations above mentioned, and for the further reason that successful results in pulling the upper both forwardly and inwardly by the use of this machine would require the exercise of a high degree of skill on the part of the operator in presenting the shoe to the machine. These limitations render it, for the most part, impractical to use the machine to accomplish what is done by hand. The hand pulling and tacking, however, restricts very considerably the output of the side-lasting

machine and takes much of the time of a highly paid operator. There is, moreover, the further objection to the hand work, as well as to the use of the side-lasting machine for the purpose, that in applying the pull first at one side of the shoe and then at the other it is only by the exercise of great care that serious distortion of the upper can be avoided.

This invention, in one important aspect, aims to overcome the difficulties and disadvantages above mentioned by providing in an upper pulling machine means for accomplishing the result that the operator of the side-lasting machine has heretofore aimed to accomplish by hand before presenting the shoe to that machine, a very important object being to produce a better shoe than heretofore by guarding against distortion of the upper and by determining in an automatic manner the direction and the force of the pull. The invention accordingly provides novel means for pulling an upper at that portion of a shoe where the side of the last and the edge of the sole curve inwardly from the ball toward the shank, in such manner as to conform the upper tightly to the contour of the last across the instep and to draw it close to the shoulder formed by the inward curvature of the side of the last and the edge of the sole at the rear of the ball line, the machine herein shown having grippers for pulling the upper thus at the opposite sides of the shoe simultaneously. The curvature above mentioned is, of course, more pronounced at the inner side of a shoe than at the outer side, and in order to accomplish the desired results at the inner side of the shoe the machine has means for imparting to the gripper at that side both a turning or twisting movement and a forward or "foredrawing" movement toward the toe, in addition to pulling movement heightwise of the shoe (frequently termed the "up-draw") and overdrawing movement inwardly over the bottom of the shoe. Experience shows that at the outer side of the shoe fore-drawing movement of the gripper may be, and preferably should be, dispensed with, and that as far as turning movement of that gripper is concerned, it may be permitted to assume whatever position is natural in re-

sponse to resistance of the upper in the over-drawing operation. In other respects both grippers may pull substantially alike. Since the opposite shoes of a pair will usually be operated upon in succession, the invention further provides automatic means for setting the parts to operate on rights and lefts alternately, the machine illustrated also having means for indicating whether the parts are set to operate on a right shoe or a left shoe, with further means whereby adjustment may be made manually to operate on a right or a left as desired.

It is a further object of the invention to provide means for fastening the upper after it has been pulled in the manner above set forth, and to this end the machine herein shown has overlaying and fastening means comprising wiper and tacker units arranged to operate substantially in the locations where the upper is pulled inwardly by the grippers at the opposite sides of the shoe. In order to hold the upper properly when it is released by the grippers and to driven the tacks in the proper relation to the edge of the shoe bottom, it is desirable that the wiping and tacking means move inwardly at each side of the shoe in a direction substantially perpendicular to that portion of the edge of the shoe bottom where the overwiping operation is performed. This necessitates that the wiper and tacker unit, operating for purposes of the present invention on that portion of the shoe which curves inwardly toward the shank, move laterally of the shoe with a component of movement toward the toe end of the shoe. The desired result is accomplished in the construction shown by means for imparting automatically to the wiper and tacker unit at each side of the shoe a turning movement during its movement laterally of the shoe, in such manner as to swing its wiper into substantially perpendicular relation to the edge of that portion of the sole where the overwiping operation is performed, the wiper and tacker unit thus assuming at the end of its wiping movement a position for driving the tacks at substantially equal distances from the edge of the sole. For reasons such as hereinbefore set forth with reference to the turning of the grippers, it is desirable that the wiper and tacker unit that operates at the inner side of a shoe have a greater component of forward movement than the unit that operates at the outer side of the shoe. The machine is accordingly provided with means for accomplishing this result, and also with means connected with the gripper controlling means for producing the desired alternation for rights and lefts.

The above and other features of the invention, including novel means for positioning and supporting the shoe and various details of construction and combinations of parts, will be more fully set forth by reference to

the accompanying drawings and pointed out in the claims.

The invention is herein illustrated in its application to a machine designed to operate on a shoe which has been previously pulled over and fastened at the toe and at the opposite sides of the forepart, and the means for pulling and for overwiping and fastening the upper is accordingly arranged to operate on the shoe only at the rear of the portions operated upon by the well-known commercial pulling-over machines. It is to be recognized, however, that in many of its aspects the invention is not restricted in utility to machines for operating upon a previously pulled-over shoe nor to means for operating upon the shoe in the particular locations herein illustrated.

In the drawings:

Fig. 1 is a view in side elevation of the head portion of a machine in which the invention is embodied, illustrating diagrammatically the position of a shoe and showing a portion of the shoe supporting means in operative position;

Fig. 2 shows the head portion of the machine as viewed from the front, with the shoe supporting means in its idle position;

Fig. 3 shows the grippers and the wiper and tacker units, with associated parts of their operating and controlling means, as viewed from below, parts of the structure being omitted and parts in section;

Fig. 4 is a front elevation of one of the wiper and tacker units and an adjacent portion of the frame of the machine;

Fig. 5 shows in side elevation and on a larger scale than Fig. 1 a portion of the operating and controlling means, with parts in section;

Fig. 6 is a section on the line 6—6 of Fig. 5, showing parts of the structure in plan;

Fig. 7 is a section on the line 7—7 of Fig. 5, with parts shown in elevation;

Fig. 8 is a section on the line 8—8 of Fig. 4;

Fig. 9 is a section on the line 9—9 of Fig. 8, illustrating more fully the shape of the cams for controlling the wiper and tacker units;

Fig. 10 is a view on an enlarged scale of a portion of the structure seen in Fig. 3, illustrating different positions of the parts; and

Fig. 11 shows the bottom of a shoe after it has been operated upon by the machine and illustrates diagrammatically different positions of the grippers.

Conveniently, as herein illustrated, a machine embodying the present invention may include in its organization a considerable portion of the structure of a well-known type of pulling-over machine the principal characteristic features of which are shown and described in detail in United States Letters Patent No. 1,029,387, granted on June 11, 1912, upon an application of R. F. McFeely,

and for a better understanding of details of the structure not hereinafter particularly described reference may be made to said patent. The machine has a sole rest 2 provided with 5 a pair of feet 4 for engaging the sole at opposite sides of the forepart, and for purposes of the present invention the sole rest has a forward extension 6 which projects downwardly into position to engage the toe 10 end face of the shoe and acts as a gage to determine the lengthwise position of the shoe when the operator presents the shoe to the machine. The sole rest 2 is carried by a holder 8 mounted for rocking movement 15 about a shaft 10, the holder having a roll 12 engaged by a cam 14 on the main cam shaft 16 for imparting to the sole rest and to the shoe a short downward movement after the machine is started, similarly to the operation 20 of pulling-over machines of the McFeely type. A return spring 17 connected to the front end of the sole rest holds the roll 12 against its cam. In the present machine the sole rest has no automatic movement lengthwise of the shoe, but is adjustable manually 25 in its holder 8 in directions lengthwise of the shoe as heretofore by rack and pinion mechanism under control of a lever arm 18 on the shaft 10. This serves in the present 30 construction to adjust the gage member 6 for different lengths of shoes. The lever 18 carries a bolt 20 provided with a flanged head running in a guideway 22 and arranged to be tightened by a nut 24 to hold the sole 35 rest in adjusted position.

In the machine herein shown the shoe is clamped against the sole rest and is thereafter upheld and prevented from tipping during the operation of the upper pulling and 40 fastening means by a stirrup-shaped shoe support which is moved manually to operative position before the machine is started. This shoe support comprises a yoke member 45 which carries a bar 28 faced with suitable cushioning material, for example rubber, for engagement with the top of the forepart of the shoe at the rear of the toe. The yoke member 26 is pivotally suspended by a rod 30 on the lower end of a bar 32 which is 50 enlarged laterally at its lower end and forked to embrace a guide plate 34 that projects upwardly from the sole rest 2. At its upper end the bar 32 is connected to a pair of crank arms 36 of a rock shaft 38 by means of a pin 55 40 which extends through a slot in the bar and bears on the lower end of a spring plunger 42 mounted in the upper end portion of the bar. Fast on one end of the rock shaft 38 is an arm 44 connected by a rod 46 to a 60 treadle (not shown). When the treadle is depressed the arms 36 are thus swung from the broken line position to the full line position of Fig. 1 and act to impart upward movement yieldingly to the bar 32 through 65 the plunger 42, at the same time swinging the upper end portion of the bar forwardly. Further to control the yoke member 26 in such manner as to position the bar 28 initially in such relation to the sole rest as not to interfere with the manual positioning of the shoe, the yoke member carries a pin 48 (Fig. 1) which projects through a curved slot 50 in the plate 34, the rod 30 being guided in a straight slot 51 in this plate. When the bar 32 is in lowered position the yoke member 26 is thus swung forwardly to the broken line position of Fig. 1, and when the bar is lifted the curved edge of the slotted portion of the plate 34 acts as a cam to swing the yoke member rearwardly to position the bar 28 under the forepart of the shoe before it is lifted far enough to engage the shoe. Further upward movement of the bar 32 then carries the member 28 into supporting engagement with the shoe. When the parts are thus positioned the crank arms 36 are on "dead center" relatively to the direction of pressure of the shoe support on the shoe, and the shoe support is thus locked in operative position against displacement by downward pressure of the shoe. As already stated, the sole rest after the starting of the machine receives a short downward movement, and this serves to clamp the shoe still more firmly upon the supporting member 28.

It is desirable to provide means for returning the shoe support automatically to its idle position after the operations on the shoe have been completed, thereby releasing the shoe, and for this purpose the arms 36 have projections 52 on which is pivotally suspended a link 54. By downward movement of this link the crank arms 36 are carried off dead center, thereby releasing the bar 32 to the action of a spring 56 which then moves the bar downwardly to impart shoe-releasing and forward swinging movement to the shoe supporting member 28. For imparting such downward movement to the link 54 the machine may conveniently utilize, as illustrated, connections heretofore utilized in one form of pulling-over machine for operating the toe gripper, these connections comprising a short lever 58 mounted to turn about a fixed pin 60 and connected by a pivot 62 to one arm of a lever 64. At its rear end the lever 64 is connected yieldingly to a cam slide 66 operated by a cam on the cam shaft 16 in a well-known manner. It will be understood that in that portion of the cycle in which the pulling of the upper takes place the front end of the short lever 58 receives an upward movement, and that it receives a return movement downwardly at the time of the return of the other parts of the machine to starting position. It is this downward movement of the lever that is utilized to effect the release of the shoe support, and to this end the lever carries a plate provided with a lower front corner or projection 68

arranged to engage a shoulder 70 on the link 54. After pulling the link downwardly enough to release the shoe support the lever 58 in its further swinging movement serves by engagement of its end face with the side 5 of the link to push the link forwardly far enough to prevent its shoulder 70 from engaging the projection 68 when the shoe support is moved by the treadle to its operative position in operating upon the next shoe. 10 Such movement of the treadle will carry the shoulder 70 upwardly beyond the projection 68, but in the first part of the cycle of the machine the lever 58 is swung upwardly far enough to reestablish its operative connection 15 with the link.

For pulling the upper the machine is provided with opposite side grippers comprising gripper jaws 72 mounted on gripper casings 74 and having gripper bars connected by ball-and-socket joints to updraw levers 76, in accordance with the well-known construction of pulling-over machines of the type hereinbefore mentioned. It will be understood that updraw movement is imparted to the levers 76 yieldingly through springs 78 by a cam-operated slide 80 and that by such movement of the levers the grippers are closed on the upper and are moved in directions heightwise of the shoe to pull the upper. In the machine illustrated the grippers are arranged to engage the upper at the rear of the portions previously operated upon in pulling over or shaping the upper at the fore-part of the shoe, and preferably in locations where the sides of the last and the edge of the sole are inclined or curved inwardly toward the shank of the shoe at the rear of the ball line, as illustrated in Fig. 11. The grippers are positioned initially far enough apart to permit the shoe to be inserted conveniently between them, and are arranged at such angles that the upper may be conveniently inserted between the jaws when the shoe is presented to the machine.

To assist in accomplishing the objects of the invention, there is provided means for imparting to that gripper which grasps the upper at the inner side of the shoe a fore-drawing movement toward the toe, as herein shown in the course of its movement heightwise of the shoe, and since one of the opposite grippers will engage the upper at the inner side of a right shoe and the other gripper at the inner side of a left shoe, each of the grippers is connected to mechanism for imparting to it such forward movement. This mechanism is in many respects similar in construction to the mechanism heretofore provided in pulling-over machines for moving the side grippers in different directions lengthwise of the shoe to straighten the tip, as set forth in detail in Patent No. 663,777 granted on Dec. 11, 1900, on an application 60 of R. F. McFeely. This mechanism com-

prises a rock shaft 82 (Figs. 3 and 5) mounted in bearings in the frame of the machine and having fast thereon a pinion 84 in operative engagement with a rack member 86 which is connected to one of the grippers. 70 Mounted to turn on the shaft 82 is a sleeve 88 having one end shaped in the form of a pinion 90 which is in operative engagement with a rack member 92 connected to the other gripper. The rack members 86 and 92 engage their pinions in the present construction on the same side of the shaft 82, and at their front ends these rack members are provided with transverse guide arms 94 in which slides 96 are mounted for movement laterally of the shoe with the grippers, these slides being connected by pivots 98 to guide members 100 that are slidably mounted in the rear sides of the gripper casings 74 so that the grippers may move relatively to the members 100 in directions heightwise of the shoe. 80

It will be understood from the foregoing description that forward movement is imparted to either gripper by movement of its rack member 86 or 92 in response to the turning of the pinion 84 or 90. For operating the pinion 84 the shaft 82 is turned by means of a gear sector 102 which engages a gear sector 104 fast on the end of the shaft 82, and for operating the pinion 90 the sleeve 88 is similarly provided with a gear sector 106 engaged by a gear sector 108 (Fig. 6). The turning movements of the shaft and the sleeve are effected respectively against the resistance of springs 110 and 112 which are arranged to maintain the grippers normally in predetermined positions lengthwise of the shoe. The gear sectors 102 and 108 receive their operative movements from a slide 114 (Figs. 1 and 5) which is mounted for horizontal movement in the frame and in that part of the cycle when the grippers receive their upper pulling movement is moved toward the left (Fig. 1) by a cam 116 on the cam shaft 16. The slide 114 has mounted thereon a bracket 118 (Figs. 5, 6 and 7) provided with a rod 120 on which are pivoted a pair of arms 122, and secured adjustably on these arms by clamping screws 124 are plates 126 provided with shoulders 128 arranged to engage the down-turned ends of arms 130 which are pivotally connected adjustably to crank arms 132 connected respectively to the different gear sectors 102 and 108. It will thus be evident that if either of the plates 126 is in position for its shoulder 128 to engage the down-turned end of its associated arm 130 upon movement of the slide 114 toward the left, it will act through the arm to impart turning movement to the corresponding gear sector 104 or 106 and will thereby impart forward movement to the corresponding gripper. It will also be understood that the extent of such forward movement of the gripper may be adjusted by adjusting the 120 125 130

plate 126 on its arm 122 or by adjusting the pivotal connection between the arm 130 and the crank arm 132 to vary the effective length of the crank arm.

5 Since, as hereinbefore explained, it is desired to impart foredrawing movement only to that gripper which engages the upper at the inner side of the shoe, the machine is provided with controlling means whereby 10 only one of the plates 126 is in position for its shoulder 128 to engage its arm 130 when the slide 114 receives its operative movement. To this end there are mounted fast on a shaft 134 which is rotatable in the movable bracket 15 118 a pair of star wheels 136 having teeth arranged to engage downturned lugs 138 on the arms 122, these arms thus resting upon the different respective star wheels against which they are held by springs 140. The 20 wheels 136 are so fixed in relation to each other that the teeth of each wheel are in radial planes which are between the teeth of the other wheel, and by reason of this staggered arrangement and the relation of 25 the lugs 138 on the arms 122 to each other, only one of these arms is at any time upraised in position for operating its associated arm 130, the lug 138 on the other arm 122 at that time resting between the teeth of the 30 corresponding wheel 136. To limit downward movement of either arm 130 when its corresponding arm 122 is in lowered position, each arm 130 carries a pin 142 which is arranged to engage a supporting shelf 144 35 formed on a bracket 146 which is fast on the frame of the machine.

To alternate the forward movements of the different grippers for operating successively on right and left shoes, the machine is provided with means which acts in each cycle 40 to turn the star wheels 136 a distance equal to half the angular interval between the successive teeth on each wheel. For this purpose there is mounted to turn on the shaft 134 a 45 pawl carrier 148 provided with a spring controlled pawl 150 arranged to engage the teeth of a ratchet wheel 152 that is fast on the shaft. The pawl carrier 148 is provided with an adjustable screw 154 arranged to engage a fixed 50 lug 156 in the return movement of the slide 114 toward the right (Fig. 5), thereby rendering the slide effective in such movement to cause the pawl 150 to act on its ratchet wheel to turn the shaft 134 the required distance. 55 A spring 158 connected to the pawl carrier serves to hold the screw 154 in engagement with the lug 156 as the slide 114 receives its operative movement toward the left, thereby causing the pawl to move over the ratchet teeth into position to effect the next advance 60 of the star wheels. The distance of such movement of the pawl is further controlled adjustably by means of a rod 160 which is pivoted to the pawl carrier and projects 65 through an opening in a lug 162 on the mov-

able bracket 118, the rod having threaded thereon a nut 164 which by engagement with the lug 162 limits the extent of the movement of the pawl relatively to its ratchet wheel when the slide 114 and its bracket 118 are moved toward the left. One of the arms 70 122 will thus be upraised in operative position in one cycle of the machine, and the other arm in the next cycle of the machine, so that the different grippers will act alternately to 75 pull the upper forwardly toward the toe in operating successively on right and left shoes.

It is desirable that the operator be enabled to ascertain at a glance whether the machine is set to operate on a right shoe or a left shoe, 80 and to this end the machine is provided with an automatically controlled signal device within view of the operator as he stands in his working position. This device comprises a pair of lever arms 166 and 168 pivoted on 85 the frame of the machine and marked respectively "Right" and "Left", these arms being connected by links 170 to the ends of pivoted lever arms 172 which have downwardly extending projections 174 arranged to rest on 90 guideways formed by lateral extensions of the plates 126 and held thereon by springs 175 connected to the arms 172. It will thus be evident that when an arm 122 and its plate 126 are upraised in operative position, the 95 corresponding signal lever 166 or 168 will likewise be raised, while the other signal lever will be in lowered position. Preferably a plate 176 will be arranged to conceal the 100 marking on the lever which is in lowered position, as illustrated in Fig. 7. If at any time the operator should desire to change the adjustment, for example to operate successively on different right shoes or on different left shoes instead of on rights and lefts alternately, he is enabled to do this by moving 105 the pawl carrier 148 manually to turn the star wheels the required distance, this distance being determined by engagement of a shoulder 178 on the rod 160 with the front 110 face of the lug 162.

For imparting to the gripper at the inner side of the shoe turning or twisting movement about an axis extending heightwise of the shoe, or substantially perpendicular to the plane of the shoe bottom, to assist in tightening the upper and in drawing it close to the side of the last and to the edge of the sole at the rear of the ball line, the machine is provided at each side (Figs. 3 and 10) with 115 an abutment member or plate 180 arranged to act on a pin 182 which is fast on an arm that projects from the member 100 hereinbefore referred to as mounted in a guideway in the rear side of the gripper casing. It will 120 be noted that each member 100 has a T-shaped portion that engages in a correspondingly shaped slideway in the gripper casing so that any turning movement of the member 100 125 about its pivotal connection 98 with the slide 130 through an opening in a lug 162 on the mov-

96 will result in corresponding turning movement of the gripper. The abutment plates 180 are substantially parallel to the guide arms 94, so that they have no turning effect 5 on the grippers in response to the inward or overdrawing movements of the latter; but when the gripper that engages the upper at the inner side of the shoe receives its foredrawing movement, the plate 180 at that side 10 acts on the pin 182 to cause the member 100 and the gripper to turn in the required direction. The plate 180 associated with the gripper that pulls at the outer side of the shoe does not interfere with such turning movement 15 of that gripper as may occur in response to differences in resistance of different portions of the upper in the overdrawing operation, and such resistance will naturally cause that gripper to turn to a position approximating a parallel relation to the adjacent portion 20 of the edge of the shoe bottom, as illustrated in Fig. 11. Experience has shown that this is all that is necessary for satisfactory results at the outer side of the shoe where the 25 curvature is much less than at the inner side. After the grippers have released the upper they are swung inwardly to idle positions out of the way of the tacking means, as is common in pulling-over machines, and in order that 30 they may not interfere with each other the abutment plates 180 are curved at their inner ends so that the pins 182 may assume positions in which the grippers are substantially or approximately in parallel relation to each 35 other at the end of their inward movements, as indicated in Fig. 11.

The inward or overdrawing movements of the grippers are effected by mechanism similar to that used heretofore in pulling-over 40 machines of the McFeely type, this mechanism comprising for each gripper a pair of springs 184 that act on a plate 186 which bears on the outer side of the gripper casing. The inward movements of the grippers are 45 controlled by gripper spacing mechanism similar to that shown and described in detail in the prior McFeely patents and including a bar 188 which is moved toward the left (Fig. 5) to release the grippers to the action 50 of their overdraw springs 184 and is subsequently moved toward the right to return the grippers to starting position. As in prior machines, this bar is controlled by a slide 190 which is a part of the means provided for im- 55 parting inward movements to the wiper and tacker units, as more fully described in the prior patents, this bar having rack teeth 192 controlled by a pinion 194. For the purposes of the present invention, however, it is con- 60 sidered preferable, for reasons hereinafter explained, to impart to the grippers their overdrawing movements at an earlier time in the cycle than has been customary heretofore in the McFeely type of pulling-over machine, 65 and the present machine is accordingly pro-

vided with novel connections between the bar 188 and the slide 190 arranged to be controlled in part by the slide 114. By reference to Fig. 5 it will be seen that there is pivoted at 196 on the rear end of the slide 190 a lever 198 provided with a lug 200 arranged to engage an upstanding lug 202 on the bar 188, the lever 198 being pressed downwardly by a spring 204. By this means the slide 190 acts normally to hold the bar 188 in its forward position with the grippers in outspread or normally spaced relation. To permit the overdrawing movements of the grippers the lever 198 is swung upwardly into position to release the lug 202 by the action of a lever arm 206 which is fast on a rock shaft 208 and has a projection 210 positioned under the outer end of the lever 198. Fast on the shaft 208 is an arm 212 provided with a pin 214 that projects into a slot formed in a lever 216. The lever 216 has an arm that projects downwardly into position to be engaged by an end of the rod 120 which, as already explained, is carried by the bracket 118 that moves with the slide 114. The lever 216 and the rod 120 are arranged in such relation that the rod will engage the lever when the slide 114 has arrived nearly at the end of its operative movement, and by further movement of the slide the lever will be turned into position to effect the release of the bar 188. It will thus be evident that the overdrawing of the upper will take place substantially at the end of the updrawing and foredrawing operation after the grippers have been moved upwardly far enough to avoid contact with the edge of the sole. It will be understood that in the return of the parts to starting position the lug 200 will again engage the lug 202 and impart the required return movement to the bar 188.

Each of the two opposite wiper and tacker units comprises an arm 218 arranged to be moved laterally of the shoe by connections to the slide 190, as more fully described in the prior patents, and having mounted thereon a tack driver bar 220 likewise operated and controlled in the manner common heretofore. For purposes of this invention the lower end of each arm 218 is shaped to provide a downwardly extending cylindrical bearing 222 for a rotatable wiper and tacker block 224, the latter being held in position for turning movement about the bearing 222 by means of a bearing screw 226. The block 224 has mounted thereon the usual tack holders 228 supplied automatically with tacks in the same manner as in prior pulling-over machines, and tack drivers 230 carried by a slide 232 which in any position of the block 224 is in operative relation to an operating member 234 on the lower end of the driver bar 220. In the construction shown each of the wiper and tacker units is arranged to drive two tacks, although the invention is not depend-

ent upon the use of any particular number of tacks. Below the tack holders is a wiper 236 provided with a cylindrical shank 238 mounted in a socket formed in a wiper holder 240, the latter being mounted on a pivot 242 in the lower end of the block 224. A spring 244 connected to the wiper holder acts to position the wiper normally as indicated in Fig. 4, while permitting the wiper to tip upwardly in response to its engagement with the shoe for wiping the upper over the edge of the sole. The shank 238 of the wiper may turn in the wiper holder to permit the wiper to adjust itself to the inclination of the shoe bottom, such turning movement being limited by a clamp 246 which is secured to the outer end of the shank and is forked for engagement with opposite sides of a plate 248 that is secured to the wiper holder. The clamp 246 also serves to limit inward movement of the wiper relatively to the wiper holder, and a spring 250 is arranged to hold the wiper normally at the limit of movement thus determined, as illustrated in Fig. 4, while permitting the wiper to yield upon engagement with the shoe. The wiper is provided with a shoulder 252 which limits its inward movement over the shoe. This affords a simple and effective means for wiping the upper in and for holding it until it is fastened by the tacks, but the invention is not dependent upon the use of overwiping means of this particular construction.

It is by the turning of the wiper and tacker blocks 224 about their bearings 222, in the machine herein shown, that the wipers are made to operate each with a component of movement forwardly toward the toe so as to act in directions substantially perpendicular to the portions of the edge of the sole where they are located, such turning movement of the blocks 224 resulting also in positioning the tacks at substantially uniform distances from the edge of the sole. In the construction shown turning movements of the required extent are imparted to the wiper and tacker blocks 224 by the action of cam members 254 upon lever arms 256, the latter being mounted at one end upon pivots 258 carried by lugs on the lower ends of the arms 218 and connected at the other end by slidably couplings 260 to projections 262 on the blocks 224. Between its ends each lever 256 carries a roll 264 for engagement with the cam. It will thus be seen that as each wiper and tacker unit moves inwardly toward the shoe, its wiper and tackers will be turned in the required direction by the action of the cam member 254 on the lever 256, as indicated by Fig. 8.

As previously stated, it is desired that the wiping and tacking means that acts at the inner side of a shoe shall have a greater component of forward movement than the means that acts at the outer side of the shoe, and

each of the cam members 254 is accordingly provided with cam faces *a* and *b* positioned substantially at right angles to each other, as illustrated in Fig. 9, and the machine has means for positioning the different cam members in such relation to each other and for controlling them in such manner that the wiping and tacking means at the inner side of a shoe will be turned by the portion *a* of its cam member while the wiping and tacking means at the opposite side of the shoe is turned by the portion *b* of its cam, whatever shoe is presented for treatment. To this end, the cam members 254 are mounted to turn in bearings in the frame and are connected by lever arms 266 and links 268 to arms 270 and 272 fastened respectively to the rock shaft 82 and the sleeve 88 previously described as a part of the means for effecting and alternating the foredrawing movements of the grippers. It will be readily understood that these connections to the cam members are such as to alternate the turning movements of the wiping and tacking mechanisms for right and left shoes with the corresponding alternation of the gripper movements. To maintain the rolls 264 in engagement with their cam members, the levers 256 are engaged on their inner sides by spring plungers 274 which are mounted in the arms 218.

In the operation of the machine, briefly summarized, the operator presents a shoe, the upper of which has been previously tensioned or shaped to the last and fastened at the toe, in the position indicated in Fig. 1 with its toe end against the gage member 6, and then depresses the treadle rod 46 to move the shoe supporting member 28 into clamping engagement with the shoe. If the shoe previously operated upon by the machine was, for example, a right shoe, the shoe presented will be a left shoe; or if it should be desired to operate upon another right shoe, the machine will be correspondingly set by a manual movement of the pawl carrier 148, as hereinbefore explained. Upon the starting of the machine the grippers are operated to grip and to pull the upper at the opposite sides of the shoe, and during the updraw movement of the grippers the gripper that pulls at the inner side of the shoe receives a foredrawing movement and a simultaneous turning movement into position for its jaws to extend in substantially parallel relation to the corresponding portion of the sole edge. Substantially at the end of the updraw movement of the grippers they have imparted to them their overdrawing movements, during which the outer side gripper may also turn more or less, the gripper jaws assuming, at the end of the overdraw, positions substantially as indicated by broken lines in Fig. 11.

The machine herein shown is so controlled as to come automatically to a stop before the grippers release the upper, as has been

customary heretofore in pulling-over machines, although it is contemplated that under some conditions such a stop may be unnecessary. During this pause in the operation of the machine the operator is enabled to inspect the upper, and if necessary he may adjust the upper on the last by manual movements of the side gripper levers. In determining whether conditions are such as to require adjustment of the upper the operator is assisted by the fact that the upper is held in overdrawn condition, substantially in the position in which it is to be tacked. It is to be recognized that in this among other respects the invention is not limited in its advantages to a machine which pulls the upper in the particular locations herein shown, but is of more general utility in pulling-over machines.

When the machine is again started side clamping pads 276 which are carried by arms 278 similar to the side clamp arms of prior pulling-over machines are moved inwardly into engagement with the shoe at the rear of the manually operated shoe support. As the machine continues its cycle the wiping and tacking mechanisms are moved inwardly and turned as hereinbefore explained, the grippers being released from the upper as soon as the wipers have arrived in effective holding engagement with the shoe in response to the action of the inwardly moving tacking means upon latches 280 on the grippers. When the wiping and tacking mechanisms have arrived in proper position for driving the tacks, the tack driving means is made to operate in the usual manner, and the parts of the machine are thereupon returned to starting position, the parts being set automatically to operate next upon the other shoe of the pair.

It is contemplated that the invention will be utilized with important advantages in operating not only upon welt shoes, as herein illustrated, but also upon other kinds of shoes including McKay-sewed shoes and turn shoes. After the upper has been pulled over and fastened in the manner illustrated the shoe is ready to be presented without further treatment to the side-lasting machine. It is contemplated, moreover, that with some shoes, for example turn shoes of the smaller sizes or other shoes where the style of last renders it practical, the shoe may be directly presented to a machine for sewing the upper to the sole without the intervening operation of side lasting.

Having described the invention, what I claim as new and desire to secure by Letters

60 Patent of the United States is:

1. In a machine of the class described, the combination with shoe positioning means, of upper pulling means comprising a gripper so positioned as to grip the upper at that portion of the shoe where the side of the

last and the edge of the sole curve inwardly from the ball toward the shank, and means for imparting to said gripper in the course of the upper pulling operation turning movement about an axis extending heightwise of the shoe to draw the upper inwardly toward the side of the last at the rear of the ball line. 70

2. In a machine of the class described, the combination with shoe positioning means, of upper pulling means comprising a gripper so positioned as to grip the upper at that portion of the shoe where the side of the last and the edge of the sole curve inwardly from the ball toward the shank, means for effecting relative movement of the gripper and the last to pull the upper heightwise of the last, and means for imparting to said gripper in the course of said relative movement turning movement about an axis extending heightwise of the shoe to carry the rear ends of its jaws nearer to the longitudinal median line of the shoe than the front ends of the jaws. 85

3. In a machine of the class described, the combination with shoe positioning means, of upper pulling means comprising a gripper so positioned as to grip the upper at that portion of the shoe where the side of the last and the edge of the sole curve inwardly from the ball toward the shank, means for effecting relative movement of said gripper and the last to pull the upper heightwise of the last, and mechanism automatically operative in time relation to said relative movement of the gripper and the last to impart to the gripper turning movement about an axis extending heightwise of the shoe to pull the upper at the rear of the gripper jaws inwardly toward the side of the last. 95 100

4. In a machine of the class described, the combination with shoe positioning means, of upper pulling means comprising a gripper so positioned as to grip the upper at that portion of the shoe where the side of the last and the edge of the sole curve inwardly from the ball toward the shank, means for effecting relative movement of said gripper and the last to pull the upper heightwise of the last, means for moving said gripper inwardly to draw the upper over the edge of the sole, and mechanism automatically operative to turn said gripper about an axis extending heightwise of the shoe to carry its jaws into substantially parallel relation to that portion of the edge of the sole over which the upper is pulled inwardly in the overdrawning operation. 115 120

5. In a machine of the class described, the combination with shoe positioning means, of upper pulling means comprising a gripper so positioned as to grip the upper at that portion of the shoe where the side of the last and the edge of the sole curve in- 125 130

wardly from the ball toward the shank, and means for imparting to said gripper in automatically determined time relation to each other turning movement about an axis extending heightwise of the shoe and overdrawing movement inwardly over the bottom of the shoe.

6. In a machine of the class described, the combination with shoe positioning means, of upper pulling means comprising a gripper so positioned as to grip the upper at that portion of the shoe where the side of the last and the edge of the sole curve inwardly from the ball toward the shank, means for imparting to said gripper updrawing movement to pull the upper and turning movement to carry its jaws into substantially parallel relation to said inwardly curved edge of the sole, and mechanism automatically operative thereafter to move the gripper inwardly over the bottom of the shoe to overdraw the upper.

7. In a machine of the class described, the combination with shoe positioning means, of upper pulling means comprising a gripper so positioned as to grip the upper at that portion of the shoe where the side of the last and the edge of the sole curve inwardly from the ball toward the shank, and means for imparting to said gripper in automatically determined time relation to one another updrawing, overdrawing and twisting movements.

8. In a machine of the class described, the combination with shoe positioning means, of upper pulling means comprising a gripper so positioned as to grip the upper at that portion of the shoe where the side of the last and the edge of the sole curve inwardly from the ball toward the shank, and operating means for said gripper comprising mechanism for moving it inwardly over the bottom of the last and mechanism for turning it in the course of the upper pulling operation to carry the rear ends of its jaws farther inwardly than the front ends for drawing the upper tightly over the shoulder formed by the inward curvature of the last and the sole at the rear of the ball line.

9. In a machine of the class described, the combination with shoe positioning means, of upper pulling means comprising a gripper so positioned as to grip the upper at that portion of the shoe where the side of the last and the edge of the sole curve inwardly from the ball toward the shank, and means for imparting to said gripper foredrawing movement toward the toe end of the shoe and turning movement about an axis extending heightwise of the shoe to draw the upper close to the side of the last at the rear of the ball line.

10. In a machine of the class described, the combination with shoe positioning means, of upper pulling means comprising a gripper so

positioned as to grip the upper at that portion of the shoe where the side of the last and the edge of the sole curve inwardly from the ball toward the shank, and means for imparting to said gripper substantially simultaneously a foredrawing movement toward the toe of the shoe and a turning movement to carry the rear ends of the gripper jaws inwardly toward the longitudinal median line of the shoe.

11. In a machine of the class described, the combination with shoe positioning means, of upper pulling means comprising a gripper so positioned as to grip the upper at that portion of the shoe where the side of the last and the edge of the sole curve inwardly from the ball toward the shank, and means for operating said gripper to pull the upper forwardly toward the toe of the shoe and inwardly over the sole and for turning it about an axis extending heightwise of the shoe to position its jaws in substantially parallel relation to the inwardly curved edge of the sole.

12. In a machine of the class described, the combination with shoe positioning means, of upper pulling means comprising a gripper so positioned as to grip the upper at that portion of the shoe where the side of the last and the edge of the sole curve inwardly from the ball toward the shank, and operating means for imparting to said gripper in time relation foredrawing, overdrawing and turning movements.

13. In a machine of the class described, the combination with shoe positioning means, of upper pulling means comprising a gripper so positioned as to grip the upper at that portion of the shoe where the side of the last and the edge of the sole curve inwardly from the ball toward the shank, means for moving said gripper toward the toe of the shoe and for turning it about an axis extending heightwise of the shoe, and mechanism automatically operative in time relation to the turning of the gripper to move it inwardly over the bottom of the shoe to draw the upper over the edge of the sole.

14. In a machine of the class described, the combination with shoe positioning means, of upper pulling means comprising a gripper for gripping the upper at the side of the shoe, means for moving said gripper forwardly toward the toe of the shoe, and mechanism automatically operative in response to the forward movement of the gripper to turn it about an axis extending heightwise of the shoe.

15. In a machine of the class described, the combination with shoe positioning means, of upper pulling means comprising a gripper for gripping the upper at the side of the shoe, a gripper turning device connected to said gripper, and an abutment arranged to act upon said device in response to the forward movement of the gripper to turn the

gripper about an axis extending heightwise of the shoe.

16. In a machine of the class described, the combination with shoe positioning means, of upper pulling means comprising a gripper for gripping the upper at the side of the shoe, a gripper guide relatively to which the gripper is movable heightwise of the shoe, means for moving said guide and the gripper forwardly toward the toe of the shoe, and a relatively stationary abutment arranged to act on said guide in its forward movement to turn the gripper about an axis extending heightwise of the shoe.

17. In a machine of the class described, the combination with shoe positioning means, of upper pulling means comprising a gripper for gripping the upper at the side of the shoe, means for guiding said gripper to move heightwise of the shoe and inwardly over the bottom of the shoe comprising parts one of which is pivoted to the other and is slidingly connected to the gripper, means for moving said guiding means and the gripper forwardly toward the toe of the shoe, and a member arranged to act on said pivoted part of the guiding means in the forward movement of the gripper to turn the gripper about an axis extending heightwise of the shoe.

18. In a machine of the class described, the combination with shoe positioning means, of upper pulling means comprising a gripper so positioned as to grip the upper at that portion of the shoe where the side of the last and the edge of the sole curve inwardly from the ball toward the shank, means for imparting to said gripper inward movement to draw the upper over the edge of the sole, and automatic means for turning said gripper to position its jaws in substantially parallel relation to that portion of the edge of the sole over which the upper is pulled and for maintaining the jaws in that relation during the overdrawing movement of the gripper.

19. In a machine of the class described, the combination with shoe positioning means, of upper pulling means comprising grippers for pulling the upper respectively at the opposite sides of the shoe, means for imparting up-draw movement to said grippers, and automatic means operative independently of the updraw movement of the grippers for imparting to one of said grippers alone fore-drawing movement toward the toe of the shoe.

20. In a machine of the class described, the combination with shoe positioning means, of grippers for pulling the upper respectively at the opposite sides of the shoe including a gripper so positioned as to grip the upper at the inner side of the shoe in the location where the side of the last and the edge of the sole curve inwardly from the ball toward the shank, and automatic means for imparting to said inner side gripper foredrawing movement toward the toe of the shoe.

ing to said inner side gripper foredrawing movement toward the toe of the shoe.

21. In a machine of the class described, the combination with shoe positioning means, of grippers for pulling the upper respectively at the opposite sides of the shoe including a gripper so positioned as to grip the upper at the inner side of the shoe in the location where the side of the last and the edge of the sole curve inwardly from the ball toward the shank, and operating means for said grippers comprising mechanism for imparting to said inner side gripper at an automatically determined time in the operation of the machine turning movement about an axis extending heightwise of the shoe to pull the upper at the rear of the ball line inwardly toward the side of the last.

22. In a machine of the class described, the combination with shoe positioning means, of grippers for pulling the upper respectively at the opposite sides of the shoe including a gripper so positioned as to grip the upper at the inner side of the shoe in the location where the side of the last and the edge of the sole curve inwardly from the ball toward the shank, and means for imparting to said inner side gripper foredrawing movement toward the toe of the shoe and turning movement to pull the upper close to the shoulder formed by the inward curvature of the last and the edge of the sole at the rear of the ball line.

23. In a machine of the class described, the combination with shoe positioning means, of upper pulling means comprising grippers for gripping the upper respectively at the opposite sides of the shoe substantially in locations where the sides of the last and the edge of the sole curve inwardly from the ball toward the shank, means for imparting to said opposite side grippers inward movements to draw the upper over the sole, and means for imparting to that gripper which grips the upper at the inner side of the shoe foredrawing movement and turning movement about an axis extending heightwise of the shoe.

24. In a machine of the class described, the combination with shoe positioning means, of upper pulling means comprising grippers for gripping the upper respectively at the opposite sides of the shoe substantially in locations where the sides of the last and the edge of the sole curve inwardly from the ball toward the shank, means for imparting to said opposite side grippers inward movements to draw the upper over the edge of the sole while permitting the gripper at the outer side of the shoe to turn in response to resistance of the upper, and mechanism for imparting to the gripper at the inner side of the shoe turning movement of predetermined extent to position its jaws in substantially parallel relation to said inwardly curved edge of the sole.

25. In a machine of the class described,

- the combination with shoe positioning means, of grippers for pulling the upper respectively at the opposite sides of the shoe including a gripper so positioned as to grip the upper at the inner side of the shoe in the location where the side of the last and the edge of the sole curve inwardly from the ball toward the shank, and means for imparting to said inner side gripper twisting and foredrawing movements and overdrawing movement to pull the upper over the shoulder formed by the inward curvature of the side of the last and the edge of the sole at the rear of the ball line. 5
26. In a machine of the class described, the combination with shoe positioning means, of opposite side grippers, and means for imparting to said grippers independently of control by the operator or by the shoe upper pulling movements differing in direction for right and left shoes respectively. 15
27. In a machine of the class described, the combination with shoe positioning means, of opposite side grippers, operating means for imparting to said grippers upper pulling movements differing in direction for right and left shoes respectively, and automatic means for setting said operating means to operate on right and left shoes alternately. 25
28. In a machine of the class described, the combination with shoe positioning means, of opposite side grippers, operating means for imparting to said grippers upper pulling movements differing in direction for right and left shoes respectively, and automatic means for setting said operating means to operate on right and left shoes alternately comprising mechanism adapted to be manipulated by the operator to condition the machine for operating on either a right or a left selectively. 30
29. In a machine of the class described, the combination with shoe positioning means, of opposite side grippers, different operating mechanisms associated respectively with the different grippers for imparting to each gripper movement in a predetermined direction, an operating member common to the different grippers, and means for connecting said member to one or the other of the different gripper operating mechanisms for operating respectively on right or left shoes. 35
30. In a machine of the class described, the combination with shoe positioning means, of opposite side grippers, means for imparting to both of said grippers updrawing and overdrawing movements in operating on different shoes, and foredrawing mechanisms associated respectively with the different grippers and operative alternately in the use of the machine on right and left shoes to impart to the gripper engaging the upper at the inner side of the shoe foredrawing movement toward the toe of the shoe. 45
31. In a machine of the class described, the combination with shoe positioning means, of opposite side grippers, mechanisms for imparting respectively to the different grippers foredrawing movement toward the toe of the shoe, and means for rendering one of said mechanisms operative in the use of the machine on a right shoe and the other of said mechanisms operative in the use of the machine on a left shoe. 50
32. In a machine of the class described, the combination with shoe positioning means, of opposite side grippers, and means for imparting automatically to the gripper at one side a twisting movement in operating on a right shoe and to the gripper at the other side a twisting movement in operating on a left shoe. 55
33. In a machine of the class described, the combination with shoe positioning means, of opposite side grippers, devices connected respectively to the different grippers for turning them about axes extending heightwise of the shoe, and means for rendering said different devices alternately operative in the use of the machine on right and left shoes. 60
34. In a machine of the class described, the combination with shoe positioning means, of opposite side grippers, operating mechanisms associated respectively with the different grippers for imparting to them foredrawing and twisting movements, and automatic means for rendering said different mechanisms alternately operative in successive cycles of the machine. 65
35. In a machine of the class described, the combination with shoe positioning means, of opposite side grippers for gripping the upper substantially in locations where the sides of the last and the edge of the sole curve inwardly from the ball toward the shank of the shoe, and means for imparting foredrawing and twisting movements to one of said grippers in operating on a right shoe and to the other of said grippers in operating on a left shoe. 70
36. In a machine of the class described, the combination with shoe positioning means, of opposite side grippers for gripping the upper substantially in locations where the sides of the last and the edge of the sole curve inwardly from the ball toward the shank of the shoe, different operating mechanisms for the different respective grippers to move them forwardly and turn them about axes extending heightwise of the shoe, and means for rendering one of said operating mechanisms effective in operating on a right shoe and the other mechanism effective in operating on a left shoe. 75
37. In a machine of the class described, the combination with shoe positioning means, of opposite side grippers for gripping the upper substantially in locations where the sides of the last and the edge of the sole curve inwardly from the ball toward the shank of the shoe, and means for imparting to one of said grippers or the other, accordingly as a right 80

or a left shoe is presented for treatment, movement to pull the upper at the inner side of the shoe forwardly and inwardly over the shoulder formed by the inward curvature of the last and the sole edge at the rear of the ball line.

38. In a machine of the class described, the combination with shoe positioning means, of grippers for pulling the upper respectively at the opposite sides of the shoe including a gripper so positioned as to pull the upper over the shoulder formed by the inward curvature of the side of the last and the edge of the sole at the rear of the ball of the shoe, and upper fastening means movable inwardly over the shoe with a component of movement forwardly toward the toe into position to fasten the upper at said inwardly curved portion of the sole.

39. In a machine of the class described, the combination with shoe positioning means, of grippers for pulling the upper respectively at the opposite sides of the shoe including a gripper so positioned as to pull the upper over the shoulder formed by the inward curvature of the side of the last and the edge of the sole at the rear of the ball of the shoe, overlaying and fastening means comprising a wiper and tacker unit for overwiping and fastening the upper at said inwardly curved portion of the sole, and means for moving said wiper and tacker unit inwardly over the shoe with a component of movement forwardly toward the toe of the shoe.

40. In a machine of the class described, the combination with shoe positioning means, of grippers for pulling the upper respectively at the opposite sides of the shoe including a gripper so positioned as to pull the upper over the shoulder formed by the inward curvature of the side of the last and the edge of the sole at the rear of the ball of the shoe, and means for overlaying and fastening the upper at said inwardly curved portion of the sole, said overlaying and fastening means being movable inwardly over the shoe in a direction substantially perpendicular to that portion of the edge of the sole where the fastening of the upper takes place.

41. In a machine of the class described, the combination with shoe positioning means, of grippers for pulling the upper at the opposite sides of the shoe, and means for wiping the upper inwardly and for fastening it at that portion of the shoe where the side of the last and the edge of the sole curve inwardly from the ball toward the shank, said wiping and fastening means being movable inwardly over the shoe with a component of forward movement toward the toe to act on the upper in a direction substantially perpendicular to that portion of the edge of the sole where the fastening of the upper takes place.

42. In a machine of the class described, the combination with shoe positioning means, of

means for pulling the upper over the shoulder formed by the inward curvature of the side of the last and the edge of the sole extending from the ball toward the shank of the shoe, a device for wiping the upper inwardly and fastening it at said inwardly curved portion of the sole, and means for moving said device inwardly and for turning it about an axis extending heightwise of the shoe to position it in proper relation to that portion of the edge of the sole where the fastening of the upper takes place.

43. In a machine of the class described, the combination with shoe positioning means, of means for pulling the upper over the shoulder formed by the inward curvature of the side of the last and the edge of the sole extending from the ball toward the shank of the shoe, and means for overlaying and fastening the upper at said inwardly curved portion of the sole, said overlaying and fastening means comprising a wiper and tacker device mounted to turn about an axis extending heightwise of the shoe, and means for moving said device inwardly over the shoe and for turning it about said axis in response to its inward movement to bring it into proper relation to that portion of the shoe where the fastening of the upper takes place.

44. In a machine of the class described, the combination with shoe positioning means, of means for pulling the upper over the shoulder formed by the inward curvature of the side of the last and the edge of the sole extending from the ball toward the shank of the shoe, and means for overlaying and fastening the upper at said inwardly curved portion of the sole, said overlaying and fastening means comprising a member mounted to turn about an axis extending heightwise of the shoe and having a wiper and tacking means thereon, means for moving said member inwardly toward the shoe, and mechanism arranged to act on said member in its inward movement to turn it about its axis in a direction to swing the shoe engaging portion of the wiper forwardly toward the toe of the shoe.

45. In a machine of the class described, the combination with shoe positioning means, of means for pulling the upper at the side of the shoe, a side tacker arm movable laterally of the shoe, a member mounted on said arm to turn about an axis extending heightwise of the shoe and having a wiper and tacking means thereon, and a cam arranged to act on said member in response to movement of the tacker arm inwardly toward the shoe to turn the member about its axis for positioning the wiper and the tacking means relatively to the shoe.

46. In a machine of the class described, the combination with shoe positioning means, of means for pulling the upper at the side of the shoe, a side tacker arm movable laterally

of the shoe, a member mounted on said arm for turning movement about an axis extending heightwise of the shoe and having a wiper and tacking means thereon, a lever pivoted on said tacker arm and connected to said member, and a cam arranged to act on said lever in the movement of the tacker arm inwardly toward the shoe to turn said member about its axis for positioning the wiper and 10 the tacking means relatively to the shoe.

47. In a machine of the class described, the combination with shoe positioning means, of upper pulling means comprising a gripper so positioned as to grip the upper at that portion of the shoe where the side of the last and the edge of the sole curve inwardly from the ball toward the shank, means for imparting to said gripper in the course of the upper pulling operation: turning movement about 20 an axis extending heightwise of the shoe to draw the upper inwardly toward the side of the last at the rear of the ball line, and means for fastening the upper at said inwardly curved portion of the sole.

48. In a machine of the class described, the combination with shoe positioning means, of upper pulling means comprising a gripper so positioned as to grip the upper at that portion of the shoe where the side of the last and 30 the edge of the sole curve inwardly from the ball toward the shank, means for imparting to said gripper turning movement about an axis extending heightwise of the shoe to draw the upper inwardly toward the side of the 35 last at the rear of the ball line, and upper fastening means movable inwardly over the shoe with a component of movement forwardly toward the toe into position to fasten the upper at said inwardly curved portion of the sole.

49. In a machine of the class described, the combination with shoe positioning means, of upper pulling means comprising a gripper so positioned as to grip the upper at that portion of the shoe where the side of the last and 45 the edge of the sole curve inwardly from the ball toward the shank, means for imparting to said gripper turning movement about an axis extending heightwise of the shoe to draw the upper inwardly toward the side of the 50 last at the rear of the ball line, a wiper and tacker device movable inwardly over the shoe into position to fasten the upper at said inwardly curved portion of the sole, and means for turning said wiper and tacker device 55 about an axis extending heightwise of the shoe to bring it into proper relation to that portion of the edge of the sole where the fastening of the upper takes place.

50. In a machine of the class described, the combination with shoe positioning means, of means for pulling the upper at the opposite sides of the shoe simultaneously including a gripper and means for operating it to pull the upper forwardly and inwardly at the inner side of the shoe over the edge of the sole

where said edge curves inwardly toward the shank at the rear of the ball line, and means for inserting a fastening to fasten the upper at said inwardly curved portion of the sole.

51. In a machine of the class described, the combination with shoe positioning means, of upper pulling means comprising a gripper so positioned as to grip the upper at that portion of the shoe where the side of the last and the edge of the sole curve inwardly from the ball toward the shank, means for imparting to said gripper foredrawing and turning movements and inward movement to pull the upper over said inwardly curved portion of the last and the sole, and overlaying and fastening means movable inwardly over substantially the same portion of the shoe as said gripper with a component of movement forwardly toward the toe of the shoe. 70

52. In a machine of the class described, the combination with shoe positioning means, of means for pulling the upper at the opposite sides of the shoe, and means for laying the upper inwardly and for fastening it in locations where the edge of the sole curves inwardly from the ball toward the shank of the shoe comprising overlaying and fastening devices movable laterally of the shoe at its opposite sides each with a component of movement forwardly toward the toe of the shoe. 80

53. In a machine of the class described, the combination with shoe positioning means, of upper pulling means comprising opposite side grippers arranged to grip the upper substantially in locations where the sides of the last and the edge of the sole curve inwardly from the ball toward the shank of the shoe, operating means for said grippers constructed to impart to the gripper at the inner side of the shoe turning movement about an axis extending heightwise of the shoe to pull the upper inwardly at the rear of the ball line, and means for overlaying and fastening the upper substantially in the locations where it is pulled by the grippers comprising an overlaying and fastening device at the inner side of the shoe movable inwardly with a component of movement forwardly toward the toe of the shoe. 90

54. In a machine of the class described, the combination with shoe positioning means, of upper pulling means comprising opposite side grippers arranged to grip the upper substantially in locations where the sides of the last and the edge of the sole curve inwardly from the ball toward the shank of the shoe, operating means for said grippers constructed to impart to the gripper at the inner side of the shoe movement forwardly and inwardly over the sole, and overlaying and fastening means comprising at the inner side of the shoe an overlaying and fastening device arranged to operate on substantially the same portion of the shoe as the inner side 100

gripper and movable inwardly over the shoe with a component of movement forwardly toward the toe.

55. In a machine of the class described, the combination with shoe positioning means, of upper pulling means comprising opposite side grippers arranged to grip the upper substantially in locations where the sides of the last and the edge of the sole curve inwardly from the ball toward the shank of the shoe, operating means for said grippers constructed to impart to the gripper at the inner side of the shoe foredrawing and turning movements, overlaying and fastening devices for the opposite sides of the shoe, and means for operating said devices constructed to impart to the device at the inner side of the shoe inward movement over the shoe and turning movement about an axis extending heightwise of the shoe to position it relatively to the shoe.

56. In a machine of the class described, the combination with shoe positioning means, of means for pulling the upper at the opposite sides of the shoe, and overlaying and fastener inserting devices movable inwardly over the shoe in locations where the edge of the sole curves inwardly from the ball toward the shank and each having a component of movement forwardly toward the toe of the shoe.

57. In a machine of the class described, the combination with shoe positioning means, of upper pulling means comprising grippers for gripping the upper substantially in locations where the sides of the last and the edge of the sole curve inwardly from the ball toward the shank of the shoe, and means for overlaying and fastening the upper in said locations comprising devices movable inwardly over the shoe each with a component of movement forwardly toward the toe of the shoe.

58. In a machine of the class described, the combination with shoe positioning means, of upper pulling means comprising grippers for gripping the upper substantially in locations where the sides of the last and the edge of the sole curve inwardly from the ball toward the shank of the shoe, overlaying and fastening devices for the opposite sides of the shoe arranged to act on the shoe in said locations, and means for moving said devices inwardly over the shoe and for turning them about axes extending heightwise of the shoe to swing their inner shoe engaging portions forwardly toward the toe of the shoe.

59. In a machine of the class described, the combination with shoe positioning means, of means for pulling the upper at the opposite sides of the shoe over portions of the last and the edge of the sole that curve inwardly from the ball toward the shank of the shoe, and overlaying and fastening devices movable inwardly over said curved portions of the shoe at its opposite sides each with a component of movement forwardly toward the toe of

the shoe, the overlaying and fastening device at the inner side of the shoe having a greater component of forward movement than the device at the outer side of the shoe.

60. In a machine of the class described, the combination with shoe positioning means, of means for pulling the upper at the opposite sides of the shoe over portions of the last and the edge of the sole that curve inwardly from the ball toward the shank of the shoe, overlaying and fastening devices movable inwardly over said curved portions of the sole at its opposite sides, and controlling means responsive to the inward movement of said devices for turning them about axes extending heightwise of the shoe to swing their inner shoe engaging portions forwardly toward the toe of the shoe, said controlling means being constructed to impart to the overlaying and fastening device at the inner side of the shoe a greater turning movement than to the device at the outer side of the shoe.

61. In a machine of the class described, the combination with shoe positioning means, of means for pulling the upper at the opposite sides of the shoe, overlaying and fastening devices movable inwardly over the shoe in locations where the edge of the sole curves inwardly from the ball toward the shank of the shoe into position for fastening the upper to the sole, and means for imparting to said overlaying and fastening devices inward movements differing in direction for right and left shoes respectively.

62. In a machine of the class described, the combination with shoe positioning means, of means for pulling the upper at the opposite sides of the shoe over portions of the last and the edge of the sole that curve inwardly from the ball toward the shank of the shoe, overlaying and fastening devices movable inwardly over said curved portions of the sole at its opposite sides into position for fastening the upper to the sole, controlling means for determining different directions of inward movement of said devices for right and left shoes respectively, and automatic means for setting said controlling means to operate on right and left shoes alternately.

63. In a machine of the class described, the combination with shoe positioning means, of means for pulling the upper at the opposite sides of the shoe over portions of the last and the edge of the sole that curve inwardly from the ball toward the shank of the shoe, overlaying and fastening devices movable inwardly over said curved portions of the sole at its opposite sides into position for fastening the upper to the sole, and controlling means for turning said devices about axes extending heightwise of the shoe to swing their inner shoe engaging portions forwardly toward the toe of the shoe, said controlling means being automatically operative in the use of the machine successively on right and

left shoes to effect a relatively greater turning movement of the overlaying and fastening device which operates at the inner side of each shoe.

64. In a machine of the class described, the combination with shoe positioning means, of means for pulling the upper at the opposite sides of the shoe over portions of the last and the edge of the sole that curve inwardly from the ball toward the shank of the shoe, overlaying and fastening devices movable inwardly over said curved portions of the sole at its opposite sides, members for controlling said overlaying and fastening devices to cause them to operate each with a component of movement forwardly toward the toe of the shoe as they move inwardly over the shoe, said members being constructed and arranged to determine for the device engaging the upper at one side of the shoe a greater component of forward movement than for the device at the other side of the shoe, and automatic means for controlling said members to cause one of said overlaying and fastening devices to receive the greater component of forward movement in operating on a right shoe and the other of said devices to receive the greater component of forward movement in operating on a left shoe.

65. In a machine of the class described, the combination with shoe positioning means, of means for pulling the upper at the opposite sides of the shoe over portions of the last and the edge of the sole that curve inwardly from the ball toward the shank of the shoe, overlaying and fastening devices movable inwardly over said curved portions of the sole at its opposite sides, cams for imparting to said devices in their inward movements turning movements about axes extending heightwise of the shoe, said cams being arranged to impart to the overlaying and fastening device at the inner side of the shoe a greater turning movement than to the device at the outer side of the shoe, and means for setting said cams to reverse the conditions of turning movement of the different devices in operating respectively on right and left shoes.

66. In a machine of the class described, the combination with shoe positioning means, of opposite side grippers, devices supported independently of said grippers for overlaying and fastening the upper at the opposite sides of the shoe, and operating means for imparting to said grippers and to said overlaying and fastening devices movements differing in direction for right and left shoes respectively.

67. In a machine of the class described, the combination with shoe positioning means, of opposite side grippers, devices for overlaying and fastening the upper at the opposite sides of the shoe, operating means for imparting to said grippers and to said overlaying and fastening devices movements differ-

ing in direction respectively at the opposite sides of the shoe, and controlling mechanism automatically operative to change the directions of said movements for operating on right and left shoes alternately.

68. In a machine of the class described, the combination with shoe positioning means, of opposite side grippers arranged to pull the upper at portions of the shoe where the sides of the last and the edge of the sole curve inwardly from the ball toward the shank, operating means for said grippers constructed to impart to the gripper engaging the upper at the inner side of the shoe fore-drawing and turning movements, overlaying and fastening devices arranged to operate on said inwardly curved portions of the shoe, means for moving said devices inwardly over the shoe and for imparting to them turning movements differing in extent at the inner and outer sides of the shoe respectively, and controlling mechanism automatically operative to condition the upper pulling and the overlaying and fastening means to operate upon a right shoe in one cycle of the machine and upon a left shoe in the next cycle of the machine.

69. A machine of the class described having, in combination, means for positioning a shoe having its upper pulled over and fastened at the toe and at the opposite sides of the forepart comprising a device for determining the lengthwise position of the shoe, and means for operating substantially simultaneously at the opposite sides of the shoe to pull over and fasten portions of the upper at the rear of the previously pulled over portions.

70. A machine of the class described having, in combination, means for positioning a shoe having its upper pulled over and fastened at the toe and at the opposite sides of the forepart comprising a device for determining the lengthwise position of the shoe, opposite side grippers arranged relatively to said shoe-positioning means to pull the upper at the rear of the previously pulled over portions substantially in locations where the sides of the last and the edge of the sole curve inwardly from the ball toward the shank of the shoe, and means for fastening the portions of the upper that are pulled by said grippers.

71. A machine of the class described having, in combination, means for positioning a shoe having its upper pulled over and fastened at the toe and at the opposite sides of the forepart, opposite side grippers arranged to pull the upper over portions of the last and the edge of the sole that curve inwardly from the ball toward the shank of the shoe, and overlaying and fastening devices associated respectively with the different grippers and supported independently of said grippers for wiping inwardly and fastening

the upper at said inwardly curved portions of the edge of the sole.

72. A machine of the class described having, in combination, means for positioning a shoe having its upper pulled over and fastened at the toe and at the opposite sides of the forepart, opposite side grippers arranged to pull the upper over portions of the last and the edge of the sole that curve inwardly from the ball toward the shank of the shoe, and overlaying and fastening devices movable inwardly over said inwardly curved portions of the edge of the sole each with a component of movement forwardly toward the toe of the shoe.

73. A machine of the class described having, in combination, means for positioning a shoe having its upper pulled over and fastened at the toe and at the opposite sides of the forepart, means for pulling the upper over the shoulder formed by the inward curvature of the side of the last and the edge of the sole at the rear of the ball line at each side of the shoe and for drawing the upper forwardly over said shoulder at the inner side of the shoe, and devices movable inwardly at the opposite sides of the shoe each with a component of forward movement toward the toe to lay the upper inwardly over said inwardly curved portions of the sole edge.

74. A machine of the class described having, in combination, means for positioning a shoe having its upper pulled over and fastened at the toe and at the opposite sides of the forepart, means for pulling the upper over the shoulder formed by the inward curvature of the side of the last and the edge of the sole at the rear of the ball line at each side of the shoe and for drawing the upper forwardly over said shoulder at the inner side of the shoe, and overlaying and fastening means including at the inner side of the shoe a wiper and tacker unit and means for moving it inwardly and for turning it to position its wiper in substantially perpendicular relation to said inwardly curved edge of the sole.

75. A machine of the class described having, in combination, means for positioning a shoe having its upper pulled over and fastened at the toe and at the opposite sides of the forepart, grippers for gripping the upper at the opposite sides of the shoe substantially in locations where the sides of the last and the edge of the sole curve inwardly from the ball toward the shank, operating means for said grippers constructed to impart to the gripper engaging the upper at the inner side of the shoe foredrawing and turning movements, and overlaying and fastening devices movable inwardly at the opposite sides of the shoe each with a component of movement forwardly toward the toe of the shoe into position to fasten the upper

at said inwardly curved portions of the sole edge.

76. A machine of the class described having, in combination, means for positioning a shoe having its upper pulled over and fastened at the toe and at the opposite sides of the forepart, grippers for gripping the upper at the opposite sides of the shoe substantially in locations where the sides of the last and the edge of the sole curve inwardly from the ball toward the shank, operating means for said grippers constructed to impart to the gripper engaging the upper at the inner side of the shoe foredrawing and turning movements, and means for fastening the portions of the upper pulled by said grippers.

77. A machine of the class described having, in combination, means for positioning a shoe having its upper pulled over and fastened at the toe and at the opposite sides of the forepart, opposite side grippers and overlaying and fastening devices arranged to operate on the shoe at the rear of the previously pulled over portions substantially in locations where the sides of the last and the edge of the sole curve inwardly from the ball toward the shank, and controlling means to cause said grippers and overlaying and fastening devices to operate differently on right and left shoe respectively.

78. A machine of the class described having, in combination, means for positioning a shoe having its upper pulled over and fastened at the toe and at the opposite sides of the forepart, opposite side grippers and overlaying and fastening devices arranged to operate on the shoe at the rear of the previously pulled over portions substantially in locations where the sides of the last and the edge of the sole curve inwardly from the ball toward the shank of the shoe, and means for imparting to said grippers and overlaying and fastening devices movements differing in direction respectively at the inner and outer sides of the shoe.

79. A machine of the class described having, in combination, means for positioning a shoe having its upper pulled over and fastened at the toe and at the opposite sides of the forepart, opposite side grippers and overlaying and fastening devices arranged to operate on the shoe at the rear of the previously pulled over portions substantially in locations where the sides of the last and the edge of the sole curve inwardly from the ball toward the shank of the shoe, means for imparting to said grippers and overlaying and fastening devices movements differing in direction respectively at the inner and outer sides of the shoe, and means for setting the machine to operate alternately on right and left shoes.

80. A machine of the class described having, in combination, means for positioning a shoe having its upper pulled over and fas-

tened at the toe and at the opposite sides of the forepart comprising a device for determining the lengthwise position of the shoe, and automatic means for gripping and pulling over and for overlaying and fastening at the opposite sides of the shoe simultaneously portions of the upper located substantially where the sides of the last and the edge of the sole curve inwardly from the ball toward the shank of the shoe.

81. A machine of the class described having, in combination, means for positioning a shoe having its upper pulled over and fastened at the toe and at the opposite sides of the forepart, said positioning means comprising a member arranged to engage the toe end face of the shoe, and devices arranged relatively to said positioning means to pull over and fasten portions of the upper at the rear of the previously pulled over portions substantially in locations where the sides of the last and the edge of the sole curve inwardly from the ball toward the shank of the shoe.

82. A machine of the class described having, in combination, means for positioning a shoe having its upper pulled over and fastened at the toe and at the opposite sides of the forepart, said positioning means comprising a member arranged to engage the toe end face of the shoe and a support arranged to engage the top of the forepart of the shoe, and devices arranged relatively to said shoe positioning means to pull over and fasten portions of the upper located substantially where the sides of the last and the edge of the sole curve inwardly from the ball toward the shank of the shoe.

83. A machine of the class described having, in combination, means for operating on a shoe having its upper pulled over and fastened at the toe and at the opposite sides of the forepart comprising devices for pulling over and fastening portions of the upper located substantially where the sides of the last and the edge of the sole curve inwardly from the ball toward the shank of the shoe, and shoe positioning means comprising a stirrup-shaped shoe support mounted for movement from an idle position substantially at the toe end of the shoe to a position in supporting engagement with the top of the forepart of the shoe.

84. A machine of the class described having, in combination, means for operating on a shoe having its upper pulled over and fastened at the toe and at the opposite sides of the forepart comprising devices for pulling over and fastening portions of the upper located substantially where the sides of the last and the edge of the sole curve inwardly from the ball toward the shank of the shoe, and shoe positioning means comprising a sole rest and a member arranged to extend across the top of the forepart of the shoe and mov-

able to clamp the shoe firmly against said sole rest.

85. In a machine of the class described, the combination with means for pulling over and fastening an upper at the opposite sides of a shoe, of a stirrup-shaped shoe support arranged to engage the shoe at the top of the forepart, said shoe support being mounted for movement relatively to the shoe in the direction of the length of the latter while the shoe is in position for the pulling-over and fastening operations.

86. In a machine of the class described, the combination with power operated means for pulling over and fastening an upper at the opposite sides of a shoe, of a stirrup-shaped shoe support movable relatively to the shoe manually from an idle position substantially in front of the toe of the shoe to a position in supporting engagement with the top of the forepart of the shoe while the shoe is in position for the pulling-over and fastening operations.

87. In a machine of the class described, the combination with means for pulling over and fastening an upper at the opposite sides of a shoe, of a stirrup-shaped shoe support mounted for swinging movement lengthwise of the shoe and for bodily movement heightwise of the shoe to carry it into supporting engagement with the top of the forepart of the shoe.

88. In a machine of the class described, the combination with means for pulling over and fastening an upper at the opposite sides of a shoe, of a shoe support for engaging the upper at the top of the forepart of the shoe, operating means connected to said shoe support for moving it bodily heightwise of the shoe, and cam mechanism responsive to movement of said operating means to swing said support lengthwise of the shoe.

89. In a machine of the class described, the combination with means for pulling over and fastening an upper at the opposite sides of a shoe, of a stirrup-shaped shoe support, an operating member on which said support is pivotally mounted to swing lengthwise of the shoe into position opposite to the top of the forepart of the shoe, means for operating said member to move said support heightwise of the shoe, and cam means for controlling said support to cause it to swing lengthwise of the shoe in response to movement of said member.

90. In a machine of the class described, the combination with means for pulling over and fastening an upper at the opposite sides of a shoe, of a shoe support mounted to move from an idle position substantially at the toe end of the shoe to a position opposite to the top of the forepart of the shoe and also to move bodily heightwise of the shoe into engagement with the top of the forepart, and treadle operated connections including a spring for

imparting yieldingly to said support movement from its idle position to its operative position.

91. In a machine of the class described, the combination with means for pulling over and fastening an upper at the opposite sides of a shoe, of a support for engaging the shoe at the top of the forepart, and means for moving said support to operative position comprising lever mechanism arranged to assume a dead-center position relatively to the direction of pressure of the shoe support on the shoe to lock said support in operative position.

92. In a machine of the class described, the combination with means for pulling over and fastening an upper at the opposite sides of a shoe, of a support for engaging the top of the forepart of the shoe, a bar connected to said shoe support, a crank arm pivotally connected to said bar, and means for moving said crank arm to dead-center position relatively to the direction of pressure of the shoe support on the shoe to lock the support in operative position.

93. In a machine of the class described, the combination with means for pulling over and fastening an upper at the opposite sides of a shoe, of a support for engaging the top of the forepart of the shoe, manual means for moving said support to operative position and for locking it in that position, and automatic means for returning the shoe support to inoperative position independently of the control of the operator after the operations on the shoe have been completed.

94. In a machine of the class described, the combination with means for pulling over and fastening an upper at the opposite sides of a shoe, of a stirrup-shaped shoe support and means for moving it into engagement with the upper at the top of the forepart of the shoe, and automatic means for imparting to the shoe movement to clamp it more firmly upon said support.

95. In a machine of the class described, the combination with means for positioning a shoe having its upper pulled over and fastened at the toe and at the opposite sides of the forepart, of means for pulling the upper at the opposite sides of the shoe at the rear of the previously pulled over portions substantially in locations where the sides of the last and the edge of the sole curve inwardly from the ball toward the shank and for drawing the upper inwardly over the sole in said locations, means for bringing the machine to a stop with the upper held in overdrawn position, means for adjusting the upper while it is thus held, and devices automatically operative when the machine is again started to fasten the upper at said inwardly curved edge of the sole.

96. A machine of the class described having, in combination, power-operated means

for pulling the upper of a previously pulled over shoe substantially in locations where the sides of the last and the edge of the sole curve inwardly from the ball toward the shank and for drawing the upper inwardly over the sole in said locations and holding it in overdrawn position for the inspection of the operator, and mechanism automatically operative upon a subsequent starting of the machine to fasten the upper in overdrawn position.

97. In an upper pulling and fastening machine constructed to come automatically to a stop at an intermediate point in the cycle, the combination of grippers for pulling the upper at the opposite sides of the last, means for effecting relative movement of said grippers and the last heightwise of the last to pull the upper, mechanism timed to operate approximately at the end of said relative movement of the grippers and the last and before the machine comes to a stop to move the grippers inwardly toward each other for drawing the upper over the bottom of the last, means for adjusting the upper on the last while it is held in overdrawn position with the machine at rest, and mechanism for fastening the upper after the machine is again started.

98. In an upper pulling and fastening machine constructed to come automatically to a stop at an intermediate point in the cycle, the combination of grippers for pulling the upper at the opposite sides of the last, overlaying and fastening devices movable inwardly at the opposite sides of the last into upper fastening position, means for effecting relative movement of said grippers and the last heightwise of the last to pull the upper, mechanism constructed and arranged to operate independently of the inward movement of said overlaying and fastening devices and approximately at the end of said relative movement of the grippers and the last to move the grippers inwardly toward each other for drawing the upper over the bottom of the last before the machine comes to a stop, means for adjusting the upper on the last while it is held in overdrawn position with the machine at rest, and means for moving said overlaying and fastening devices inwardly over the shoe after the machine is again started.

99. In an upper pulling and fastening machine, the combination with shoe positioning means, of grippers for pulling the upper over the last, devices for overlaying and fastening the upper, operating mechanism for moving said overlaying and fastening devices inwardly over the shoe, a device controlled by said operating mechanism for the overlaying and fastening devices for holding the grippers in spaced relation, and means for releasing said spacing device from control of said operating mechanism and for moving the grippers inwardly over the shoe prior to the

inward movement of the overlaying and fastening devices.

100. In an upper pulling and fastening machine, the combination with shoe positioning means, of grippers for pulling the upper over the last, overlaying and fastening devices movable inwardly over the shoe, a slide connected to said overlaying and fastening devices to move them inwardly, overdrawn springs for said grippers, a spacing device for holding the grippers spaced apart against the resistance of said springs, a member connected to said slide for holding said spacing device in normal spacing position, and means for rendering said member inoperative and for thereby releasing the grippers to the action of their overdraw springs prior to the inward movement of the overlaying and fastening devices.

101. In an upper pulling and fastening machine constructed to come automatically to a stop at an intermediate point in the cycle, the combination of grippers for pulling the upper over the last, means for effecting relative movement of said grippers and the last heightwise of the last to pull the upper before the machine comes to a stop, overlaying and fastening devices and operating mechanism for moving them inwardly over the shoe after the machine is again started, spacing mechanism controlled by said operating mechanism for the overlaying and fastening devices to hold the grippers spaced apart, and means for releasing the spacing mechanism from control of said operating mechanism to permit the overdrawing operation of the grippers prior to the intermediate stop in the cycle of the machine.

102. In a machine of the class described, the combination with shoe-positioning means, of a gripper and means for operating it to pull an upper over a last in a location where the edge of the shoe bottom extends inwardly from the ball toward the shank, and automatic means for turning said gripper about an axis extending heightwise of the shoe to position its jaws in substantially parallel relation to said inwardly extending portion of the edge of the shoe bottom.

103. In a machine of the class described, the combination with shoe-positioning means, of a gripper and means for operating it to pull an upper heightwise of a last and inwardly over a sole on the bottom of the last in a location where the side of the last and the edge of the sole extend inwardly from the ball toward the shank, and automatic means for turning said gripper about an axis extending heightwise of the shoe to position its jaws in substantially parallel relation to said inwardly extending portion of the edge of the sole.

104. In a machine of the class described, the combination with shoe-positioning means, of grippers and means for operating them to

pull an upper simultaneously at the opposite sides of a last in locations where the edge of the shoe bottom extends inwardly from the ball toward the shank, and automatic means for imparting to the gripper that pulls the upper at the inner side of the last turning movement about an axis extending heightwise of the shoe to position its jaws in substantially parallel relation to said inwardly extending portion of the edge of the shoe bottom at that side of the shoe.

105. In a machine of the class described, the combination with shoe-positioning means, of a gripper for pulling an upper at the side of a last in a location where the edge of the shoe bottom extends inwardly from the ball toward the shank, and automatic means for imparting to said gripper in the course of the operation of the machine turning movement about an axis extending heightwise of the shoe.

106. In a machine of the class described, the combination with shoe-positioning means, of opposite side grippers for pulling uppers over lasts in operating on both right and left shoes, and automatic means for imparting only to the gripper at one side an upper-pulling movement lengthwise of the last in operating on a right shoe and only to the gripper at the other side a similar movement in operating on a left shoe.

107. In a machine of the class described, the combination with shoe-positioning means, of grippers arranged respectively to pull an upper at the opposite sides of a shoe substantially in locations where the edge of the shoe bottom extends inwardly from the ball toward the shank, and upper-fastening mechanisms movable inwardly over the bottom of the shoe in those locations each in a direction inclined forwardly toward the forepart of the shoe.

108. In a machine of the class described, the combination with shoe-positioning means, of grippers arranged respectively to pull a upper at the opposite sides of a shoe substantially in locations where the edge of the shoe bottom extends inwardly from the ball toward the shank, upper-fastening mechanisms movable inwardly over the bottom of the shoe in those locations each in a direction inclined forwardly toward the forepart of the shoe, and means for operating said upper-fastening mechanisms to drive fastenings for holding the upper in tensioned condition.

109. In a machine of the class described, the combination with shoe-positioning means, of grippers arranged respectively to pull an upper at the opposite sides of a shoe substantially in locations where the edge of the shoe bottom extends inwardly from the ball toward the shank, and upper-fastening mechanisms movable inwardly over the bottom of the shoe in those locations in directions inclined forwardly toward the forepart of the

shoe with different degrees of forward inclination at the opposite sides of the shoe respectively.

110. In machines of the class described, the combination with shoe-positioning means, of grippers arranged respectively to pull an upper at the opposite sides of a shoe substantially in locations where the edge of the shoe bottom extends inwardly from the ball toward the shank, and members movable inwardly over the bottom of the shoe in those locations each in a direction inclined forwardly toward the forepart of the shoe to lay the upper over the shoe bottom.

111. In a machine of the class described, the combination with shoe-positioning means, of a gripper and means for operating it to pull an upper over a last in a location where the edge of the shoe bottom extends inwardly from the ball toward the shank, automatic means for turning said gripper about an axis extending heightwise of the shoe to position its jaws in substantially parallel relation to said inwardly extending portion of the edge of the shoe bottom, and upper-fastening mechanism also movable automatically about an axis extending heightwise of the shoe to position it in relation to said inwardly extending edge of the shoe bottom.

112. In a machine of the class described, the combination with shoe-positioning means, of a gripper and means for operating it to pull an upper over a last in a location where the edge of the shoe bottom extends inwardly from the ball toward the shank, automatic means for turning said gripper about an axis extending heightwise of the shoe to position its jaws in substantially parallel relation to said inwardly extending portion of the edge of the shoe bottom, and mechanism for fastening the portion of the upper to which the pull is applied, said fastening mechanism being movable laterally of the shoe over said inwardly extending portion of the edge of the shoe bottom in a direction inclined forwardly toward the forepart of the shoe.

113. A machine of the class described having, in combination, means for positioning a shoe the upper of which has been previously tensioned over a last and fastened at the toe end, and means constructed and arranged in such relation to said shoe-positioning means as to pull over and fasten the opposite side portions of the upper of such a shoe only in locations substantially where the edge of the shoe bottom extends inwardly from the ball toward the shank.

114. A machine of the class described having, in combination, means for positioning a shoe the upper of which has been previously tensioned over a last and fastened at the toe end, upper-pulling means constructed and arranged in such relation to said shoe-positioning means as to pull the upper at the op-

posite sides of such a shoe only in locations substantially where the edge of the shoe bottom extends inwardly from the ball toward the shank, and devices arranged to operate in those locations to lay the upper inwardly over the bottom of the last and to drive fastenings to hold it in tensioned condition.

115. A machine of the class described having, in combination, means for positioning a shoe the upper of which has been previously tensioned over a last and fastened at the toe end, upper-pulling means constructed and arranged in such relation to said shoe-positioning means as to pull the upper at the opposite sides of such a shoe only in locations substantially where the edge of the shoe bottom extends inwardly from the ball toward the shank, and overlaying and fastening devices movable inwardly over the bottom of the shoe in those locations in directions inclined forwardly toward the forepart of the shoe.

116. A machine of the class described having, in combination, means for positioning a shoe the upper of which has been previously tensioned over a last and fastened at the toe end, upper-pulling means constructed and arranged in such relation to said shoe-positioning means as to pull the upper at the opposite sides of such a shoe only in locations substantially where the edge of the shoe bottom extends inwardly from the ball toward the shank, said upper-pulling means comprising at the inner side of the shoe a gripper so controlled as to position its jaws in substantially parallel relation to the inwardly extending portion of the edge of the shoe bottom at that side of the shoe, and means for fastening the upper in said locations including at the inner side of the shoe fastening mechanism movable inwardly over the bottom of the shoe in a direction inclined forwardly toward the forepart of the shoe.

117. A machine of the class described having, in combination, means for positioning a shoe the upper of which has been previously tensioned over a last and fastened at the toe end, upper-pulling means constructed and arranged in such relation to said shoe-positioning means as to pull the upper at the opposite sides of such a shoe only in locations substantially where the edge of the shoe bottom extends inwardly from the ball toward the shank, said upper-pulling means comprising at the inner side of the shoe a gripper and means for imparting thereto foredrawing movement toward the toe end of the shoe and turning movement about an axis extending heightwise of the shoe.

In testimony whereof I have signed my name to this specification.

BERNHARDT JORGENSEN.
